UNITED STATES PATENT OFFICE.

HEINRIH GERSTMANN, OF PITTSBURG, PENNSYLVANIA.

DESIGN FOR GLASSWARE.

SPECIFICATION forming part of Design No. 12,363, dated July 19, 1881.

Application filed May 23, 1881. Term of patent 3½ years.

To all whom it may concern:

Be it known that I, HEINRIH GERSTMANN, of Pittsburgh, in the county of Allegheny and State of Pennsylvania, have invented a new and useful Improvement in Design for Glassware; and I do hereby declare the following to be a full, clear, and exact description thereof.

My improved design consists, first, of a glass dish having clear longitudinal panels, combined with alternating tufted and granular frosted longitudinal surfaces; and, second, in such a vessel having the form of a fühl-horn or cornucopia with a foot or foot and stem.

To enable others skilled in the art to produce my improved design, I will now explain it by reference to the accompanying drawings, in which—

Figure 1 is a side view of a cream-pitcher, and Fig. 2 of a footed bowl.

Like letters of reference indicate like parts in each.

The pitcher *a* is of the general form of a fühl-horn or cornucopia, with clear (and preferably fluted) longitudinal panels or surfaces *b*, alternating with tufted and granular frosted longitudinal surfaces or panels *c*. The tufted parts are seen at *c'* and the granular parts at *c''*. The pitcher has a foot, *d*, of appropriate design. A cover of the same design as the pitcher is provided, but it is necessarily broader and shallower.

Fig. 2 shows a bowl, *g*, in which the cornu-

copia is opened out much more widely than in a pitcher, celery-glass, or similar article. The cover *h* is of a similar shape. In this case a stem, *i*, and foot *k*, of suitable design, are provided, or the stem *i* may be omitted.

If preferred, a cornucopia knob or ornament, *m*, may be provided for the cover of both dishes. Other articles of glassware may be made of the same design by using the same frosted surface alternately with the clear panels, and by conforming it to the same general shape. I do not limit the use of my design as specified in first claim, however, to this shape. The result is novel, pleasing, and, for ripe fruits and flowers, especially appropriate.

What I claim as my invention, and desire to secure by Letter Patent, is—

1. A design for an article of glassware, consisting of clear longitudinal panels alternating with tufted and granular frosted panels, substantially as described and shown.

2. A design for an article of glassware, consisting of a footed cornucopia having alternate clear and tufted and granular frosted panels, substantially as described and shown.

In testimony whereof I have hereunto set my hand.

HEINRIH GERSTMANN.
